BOTTLE CAPPING MACHINE WITH MEANS
FOR CONTROLLING THE FORCE ON CAP-
PING PLUNGERSNelson Vincent Burdin, Coventry, England, as-
signor to Scotts Engineering (Newport) Lim-
ited, Newport, England

Application February 28, 1949, Serial No. 78,695

4 Claims. (Cl. 74—53)

1 The present invention relates to machines adapted to apply caps to bottles or the like, particularly to machines of the type employing a capping head in which a strip of metal foil is passed through the capping head, the blanks for the bottle caps being cut from said metal strip, after which the cap is crimped onto the bottle.

The object of the present invention is to provide a means of applying a load to the capping head by resilient means, which means can be loaded and released when desired to effect the capping operation, without undue variation of strain being incurred by the driving mechanism of the machine thus obtaining an improved output.

A further object is to provide a construction whereby resilient means operate on the bottles to minimise the possibility of fracture thereof.

In the accompanying drawings,

Figure 1 is a sectional elevation of a bottle capping machine according to the present invention, and

Figures 2 and 3 are elevations on an enlarged scale of cams employed in said machine.

Referring to the drawings, a horizontal driven cam shaft 4 is provided with two cams 5, 6 adapted to engage the lower ends of vertically disposed followers 7, 8. One cam 5, the profile of which has a gradual rise commencing from the point 9 (Figure 2), bears against the vertical follower 7 that engages the lower end of a vertically disposed compression spring 10. The other cam 6 which features a concentric portion 11 and flat portion 12 (Figure 3) along its profile engages the other vertical follower 8, which follower is pivotally secured at its upper end to one end of a substantially centrally pivoted lever 13 pivoted at 14 to a support 15 on the machine frame 16, which lever 13 has pivoted at its other end vertical links 17, these links being pivotally connected at their lower ends to a cap 18 which abuts the upper end of the compression spring 10. The cap 18 also slidably engages and is coupled to the extension 19 of the follower 7. The extension 19 is adjustable axially with respect to the follower 7.

A beam 20 pivoted on the machine frame 16 engages at one end the upper end of the compression spring 10 through the cap 18 and at 50 its other end bears on the movable capping member 21 of the capping head 22.

The arrangement is such that as the cam shaft 4 is rotated the gradual rise of the cam 5 causes a compressive force to be exerted on the spring

10 from its lower end, whilst the concentric portion 11 of the profile of the cam 6 prevents extension of the upper end of the spring 10 by reason of the follower 8, pivoted lever 13 and links 17. However, upon the follower 8 engaging the stepped down concentric portion 11 the spring 10 is released a limited degree for initial operation of the capping head 22 by means of the pivoted beam 20, whilst upon the follower 8 engaging the portion 12 of the profile of the cam 6 the spring 10 is further released to effect a final operation of the capping head 22.

Thus it will be seen that whereas the cam shaft 4 can be driven by a relatively low powered driving means to gradually load the spring 10, the said spring 10 is released to exert its accumulated load for operation of the capping head 22.

The compression spring 10 also serves the purpose of maintaining both followers 7 and 8 in contact with their respective cams 5, 6 during the main portion of the working cycle.

The follower 8 which engages the second or release cam 6 may be provided along its length with a suitable screw adjustment 23 so that its effective length may be varied and so adjust the mechanism. By varying the angular position of the two cams 5, 6 on the cam shaft 4 with respect to one another, the timing of the release of the spring 10 can be adjusted, which in turn will time the operation of the capping head 22 with respect to other operations performed by the machine.

I claim:

1. In a bottle capping machine comprising a movable capping member, a compression spring, a rotary cam shaft, a cam member mounted on said shaft, a cam follower moved by said cam member to co-act with one end of the compression spring to gradually load said compression spring, a second cam mounted on said rotary cam shaft, a second cam follower moved by said second cam member, a pivoted linkage one end of which is connected to said second cam follower, the other end of said linkage co-acting with the other end of the compression spring to release the load on said spring at a predetermined moment and a pivoted beam one end of which co-acts with the compression spring to cause said beam to move about its pivot to operate the movable capping member of the capping head of the machine.
2. In a bottle capping machine, comprising a movable capping member, a compression spring, a rotary cam shaft, a rotary cam member mounted on said shaft, a cam follower moved by said

cam member to co-act with one end of said compression spring to gradually load said spring from one end, a second rotary cam member mounted on said rotary cam shaft driven in timed relationship with the first cam member, a second cam follower moved by said second cam member, a pivoted linkage one end of which is connected to said second cam follower and the other end of which coacts with the other end of the compression spring through the pivoted linkage to release the load on said spring at a predetermined moment, and a pivoted beam one end of which co-acts with the compression spring to cause said beam to move about its pivot to operate the movable capping member of the capping head of the machine.

3. In a bottle capping machine, comprising a movable capping member, a compression spring, a rotary cam shaft, a rotary cam member mounted on said shaft, a cam follower moved by said cam member to co-act with one end of said compression spring to gradually load said spring from one end, a second rotary cam member mounted on said rotary cam shaft driven in timed relationship with the first cam member, a second cam follower moved by said second cam member, a pivoted linkage one end of which is connected to said second cam follower and the other end of which coacts with the other end of the compression spring through the pivoted linkage to release the load on said spring from the opposite end thereof at a predetermined moment, and a pivoted beam one end of which co-acts with the

5
10
15

compression spring to cause said beam to move above its pivot to operate the movable capping member of the capping head of the machine.

4. In a bottle capping machine, comprising a movable capping member, a compression spring, a rotary cam shaft, a rotary cam member mounted on said shaft, a cam follower moved by said cam member to co-act with said compression spring to gradually load said spring from one end, a second rotary cam member mounted on said rotary cam shaft and driven in timed relationship with the first cam member, a second cam follower moved by said second cam member, and pivoted linkage co-acting with the other end of the compression spring, said pivoted linkage one end of which is connected to said second cam follower to effect an initial release of load on said compression spring and a subsequent release of load on said spring in sequence, and a pivoted beam one end of which co-acts with the compression spring to cause said beam to move about its pivot to operate the movable capping member of the capping head of the machine.
